ATTORNEY

UNITED STATES PATENT OFFICE.

JEFF FLEMING, OF POINT, TEXAS.

MAIL-BAG CATCHER.

1,241,944.

Specification of Letters Patent.

Patented Oct. 2, 1917.

Application filed March 7, 1917. Serial No. 153,078.

To all whom it may concern:

Be it known that I, JEFF FLEMING, a citizen of the United States, residing at Point, in the county of Rains and State of Texas, 5 have invented new and useful Improvements in Mail-Bag Catchers, of which the following is a specification.

My invention relates to mail bag catchers and particularly to that class of mail bag 10 catchers which are employed on moving trains to catch mail bags.

My invention has for its objects; first, to provide an efficient mail catcher; second, to provide a mail catcher of such a construction 15 that it will properly catch mail bags under various adverse conditions, and thirdly, to provide a mail catcher which will properly handle mail bags of different sizes and bags having various amounts of mail 20 therein.

With these and other objects in view which will be hereinafter fully described and particularly pointed out in the claims, 25 my invention consists in the novel construction and arrangement of parts illustrated in the accompanying drawings forming a part of this specification, in which,

Figure 1 is a partial side elevation of a railway coach to which my invention is applied.

Fig. 2 is a top plan view of the mail catcher,

Fig. 3 is a sectional plan view of a portion of the mechanism.

35 Like characters of reference indicate like parts in the various views.

In the drawings 1 designates a railway coach having a doorway 2 in the side thereof. A bracket 3 is provided having an upper 40 right member 4 which engages bearings 5 and 6 which are attached to the structure of the coach in proximity with the doorway 45 therein. The bearing 5 engages the bottom of the upright member 4 of the bracket and serves both as a radial bearing and a lateral bearing. The bearing 6 serves as a radial bearing and has its under surface engaging a collar 7, mounted upon the upright member 4, whereby the bracket is prevented from upward movement. The bracket 3 has an arm 8 disposed at right angles to the upright member 4. The outer end of said arm 8 has a vertical member 9 extending at right angles thereto and upwardly therefrom.

50 A U shaped spring member 10 is provided having its sides 11 converging at a point in

termidate the ends of said sides, as designated at 12 in the drawings. The free ends of said side member 11 diverge and the ends thereof are curled outwardly as designated 60 at 13 in the drawings, for purposes herein-after described. Pivotal bearings 15 are mounted upon the sides 11 of the U shaped spring member at points intermediate the converging portion 12 thereof and the trans- 65 verse end member 14 thereon. Pivot holes 16 are formed in said pivot bearings and are disposed transversely to the said side mem- 70 bers 11. A link 17 is provided having holes therein at points near its end, and bolts 19 engage said holes of the link and the pivot holes 16, and nuts 20 screw threaded upon ends of said bolts preventing the bolts from disengaging from said holes. The vertical 75 end member 9 of the bracket 3 engages a hole 21 in the link, nuts 22, screw threaded upon said end member 9 and disposed above and below the link, preventing lateral move- 80 ment of said link upon the end member. A strut rod 23 is provided having one end con- 85 nected to the transverse end member 14 of the spring member by means of an eye bolt 24 and having its other end connected to the arm 8 of the bracket by means of a clamp 25 of usual construction, which has an ear 85 extending therefrom and engaging the end of said strut rod which is bent at right angles to the main portion thereof. A nut 27, screw threaded upon the bent over end 90 of the strut rod, prevents the strut rod from disengaging from said ear.

A collar 28 is mounted upon the upright member 4 of the bracket 3 in proximity to the upper surface of the bearing 5. A handle 29 is pivoted thereon transversely to said upright member 4. A projection 30 is provided on said handle adapted to engage a slot 31 on the upper surface of the bearing 5 when the handle is in its lowermost position. Said slot is so positioned that when the device is swung out of the doorway of the car the engagement of said projection and said slot will position the U shaped spring member for engagement with a mail bag suspended in the path of said U shaped spring mem- 100 ber. When the device is not in use the projection may be disengaged from the slot and the device swung within the car.

In the operation of the device, as the spring member 10 engages a mail bag, which 110 has been detachably suspended in the path of said spring member in the usual manner,

the diverging ends guide the bag into the inclosure of the spring member, and as the bag travels farther into the inclosure formed by the converging portion of the side members, the side members separate the required amount and the bag is firmly held therebetween. If the force with which the spring member contacts the bag is too great for the friction of the spring members upon 10 the bag to overcome, the bag contacts the link 17 and is carried along thereby, the spring member serving to firmly hold the bag from disengaging from the link. The device may then be swung within the car 15 and the mail bag disengaged from the spring members. It will be noted that by the construction of this device, the converging portions of the side members have a relatively large range of positions, respecting each 20 other, which they may assume under the various conditions in which the device is operated. This is due to the fact that the sides of the spring members are pivotally secured to the link 17, and that the spring member 25 is relatively long and that the springing qualities throughout the entire length of the spring member are available, thus allowing the converging portions 12 an almost unlimited movement. Although the spring member 30 is very long the construction of the device does not render it unwieldy or unduly heavy.

Having thus fully described my invention, I claim:—

35 1. In a device of the character described, a U shaped spring member having its sides converging at points intermediate the ends

thereof and having the free ends of said sides diverging, a link pivotally connected to the sides of said U shaped spring member 40 at points intermediate the converging portion and the transverse end member thereof, a bracket affixed to said link, and a strut rod having one end connected to the spring member and the other end thereof 45 connected to said bracket.

2. In a device of the character described, a U shaped spring member having its sides converging at points intermediate the ends thereof and having the free ends of said 50 sides diverging, a link pivotally connected to the sides of said U shaped spring member at points intermediate the converging portions and the transverse end member thereof, a bracket affixed to said link and 55 mounted for rotation, and means for locking said bracket at a predetermined position.

3. In a device of the character described, a U shaped spring member having its sides 60 converging at points intermediate the ends thereof and having the free ends of said sides diverging, a link pivotally connected to the sides of said U shaped spring member 65 at points intermediate the converging portions and the transverse end member thereof, a bracket affixed to said link and mounted for rotation, a means for locking said bracket at a predetermined position, and a strut rod having one end connected to 70 said U shaped spring member and the other end thereof connected to said bracket.

In testimony whereof I affix my signature.
JEFF FLEMING.
